UNITED STATES PATENT OFFICE.

DANIEL G. NORRIS, 2d, OF GLEN'S FALLS, NEW YORK, ASSIGNOR TO JULIA NORRIS, OF SAME PLACE, AND GEORGE E. NORRIS, OF TROY, N. Y.

NECKBAND-SHAPING DEVICE FOR BOSOM-BOARDS.

SPECIFICATION forming part of Letters Patent No. 295,180, dated March 11, 1884.

Application filed June 20, 1883. (No model.)

To all whom it may concern:

Be it known that I, DANIEL G. NORRIS, 2d, of Glen's Falls, county of Warren, and State of New York, have invented a new and useful Improvement in Neckband-Shaping Devices for Bosom-Boards, of which the following is a specification.

My invention relates to that class of devices used for shaping and distending the neckbands 10 of shirts when being ironed; and the object of my invention is to better adapt such devices for the use designed.

In the accompanying sheet of drawings, forming a part of this specification, there are shown 15 two figures illustrating my invention, with the same designation of parts by letter-reference used in both.

Figure 1 shows a perspective of a device containing my invention. Fig. 2 shows another 20 perspective of the same device with the parts turned over, to illustrate the under side of the same.

The several parts of apparatus thus illustrated are designated by letter-reference, and 25 their function explained as follows:

The letter S' indicates a U-form spring, made of elastic sheet metal, having straight sides, on which the shaping contour of the neckband is made.

30 The letters F' F' indicate two plates of like form and size, which produce the divided bottom of the device. These plates on their interior edges are straight, and on their outer rounded sides and straight ends are attached 35 to the bottom edge of the spring S', at right angles thereto, and arranged to subtend the bottom edge of the spring where attached at the sides and bent spring end of the latter, to form the flanges F' F'. The spring thus made with the 40 bend b, (the ends being turned inwardly from the sides, as indicated at a a,) and as combined with the bottom plates, exerts an elastic force to resist the forcing of the ends a a together, and it is this stored-up force, when released, 45 that is used to distend and shape the neckband of the shirt when being ironed. Within the spring S' are two blocks, B B, and each one is separately attached to the bottom plates, F'. These blocks are not hinged or pivoted, as in 50 some older devices, and are merely used to sus-

tain and support the parts and to furnish a means for securing the stored-up force of the spring S' when the ends a a are drawn in.

The letter P indicates a plate, which at its end p' is attached to one of the blocks B. The 55 other end of this plate is slotted at p'', for the passage of the threaded stud m, and the latter is provided with a thumb-screw, A, which, when screwed down, engages with the plate P, to hold it, the attached blocks, and ends of the 60 spring together against the recoil force of the latter. This arrangement of a plate and thumb-screw to hold the parts is an old device, and, apart from its position as a factor in combination, I make no claim therefor. The flanges F' 65 F' and the vertical sides of the spring S' form a right angle, and, with the flanges placed beneath the shirt-bosom where joining the neckband, an angular and positive edge is produced between the bosom and band when the iron is 70 run therein, and a kind of laundry finish that is desirable is secured.

The letter S'' indicates an auxiliary spiral spring placed between the blocks, to co-operate in connection with the exterior spring, S', 75 and it may be used, if desired, for that purpose, the said spiral spring as applied being the usual and ordinary one used in hatters' blocks; but by making the spring S' of material having the necessary amount of elasticity, the 80 spiral spring becomes superfluous.

The device thus illustrated and described is operated as follows: The ends of the spring S', as turned in and indicated at a a, are forced together against the elasticity of said spring, 85 and thus held by means of the set-screw. The device is then placed within the neck-opening of the shirt, when the force of the spring is released by turning the set-screw, and the neckband, coming in contact with the vertical sides 90 of the expanding and spreading spring, is stretched out, distended, and shaped, while the flanges F' beneath the bosom co-operate to produce at the union between the neckband and bosom a well-defined and angular line of 95 finish, as thus held when being ironed.

As the spring so made, shaped, and combined with the bottom plates and flanges will perform the same office whether the set-screw is used or some other equivalent means, and 100

as the combined parts may be used by forcing inwardly the spring ends toward each other by the hand and holding them in the latter position while being inserted in the neck-opening of the shirt, I do not limit my invention of the combined spring, flanges, and bottom plate to their combination with the set-screw.

Having thus described my invention, what I claim, and desire to secure by Letters Patent, 10 is—

1. In a neckband-shaping device, the combination of the exterior U-form sheet-metal spring, S'; the interior bottom plates, F' F', the exterior bottom flanges, F² F², and the supporting-blocks B B, constructed and arranged to 15 operate as shown and described.

2. In a neckband-shaping device, the combination of the exterior U-form sheet-metal spring, S', the interior bottom plates, F' F', the exterior bottom flanges, F² F², the interior supporting-blocks, B B, and a slotted plate and set-screw to connect the blocks, in the manner and for the purposes set forth. 20

Signed at Troy, New York, this 16th day of June, 1883, in the presence of the two witnesses. 25

DANIEL G. NORRIS, 2D.
